FOCUSING APPARATUS FOR LAMPS.
APPLICATION FILED APR. 17, 1919.

1,398,531.

Patented Nov. 29, 1921.

UNITED STATES PATENT OFFICE.

ERNEST F. WACKWITZ, OF ARLINGTON HEIGHTS, MASSACHUSETTS, ASSIGNOR TO
GRAY & DAVIS INC., OF CAMBRIDGE, MASSACHUSETTS.

FOCUSING APPARATUS FOR LAMPS.

1,398,531.

Specification of Letters Patent.

Patented Nov. 29, 1921.

Application filed April 17, 1919. Serial No. 290,803.

To all whom it may concern:

Be it known that I, ERNEST F. WACKWITZ, a citizen of the United States, residing at Arlington Heights, in the county of Middlesex and State of Massachusetts, have invented certain new and useful Improvements in Focusing Apparatus for Lamps, of which the following is a full, clear, and exact specification.

10 This invention relates to electric lamps and with regard to certain more specific features thereof to means or devices for determining the proper relative positions of the light source and its reflector.

15 One of the objects of the invention is to provide simple, inexpensive and durable means for enabling one to determine the exact relative positions of the reflector and filament of a head-light or spot light particularly for such lights used on vehicles. The use of substantially parabolic reflectors for automobile head-lights has materially increased the distance of the beam of driving light, and at the same time brought into 25 being a serious glare problem. This problem has been practically, if not wholly solved, by constructing the reflectors somewhat out of true parabolic form, by using frosted or partially opaque front glass or 30 lens, or in various other ways. The most important consideration, however, in arriving at the successful use of such devices is to obtain accurate positioning of the light filament with respect to the particular reflector with which it is employed. The present invention is designed to enable an operator to adjust his light filament to the point or region which the lamp manufacturer or builder has worked out for him, as 35 40 the one which will secure the best results.

Another object of the invention resides in the provision of visual means forming a part of the reflector for indicating the relative positions of the lamp filament and the 45 focal point of the reflector.

Still another object is to provide for the indication of the position of the filament relatively to the focal axis in a plane transversely of said axis as well as the position of 50 the filament along said axis.

Other objects will be in part obvious and in part particularly pointed out herein.

The invention accordingly consists of various features of construction, combinations of elements and arrangements of parts 55

which will be exemplified by the construction hereinafter set forth, and the scope of the application of which will be indicated in the following claims.

In the drawings wherein a number of the 60 various possible embodiments of the invention are shown:

Figure 1 is a view in cross section of a lamp including a parabolic reflector and its casing;

Fig. 2 is a sectional view taken on the line 2—2 of Fig. 1 looking in the direction of the arrows;

Fig. 3 is a plan view looking downwardly on the reflector of Fig. 1;

Fig. 4 is a fragmentary view of a modified form of the invention;

Figs. 5 and 6 are views illustrating still another modification of the invention, and

Figs. 7 and 8 are fragmentary views of 75 the mechanism for laterally adjusting the light source.

Referring now more particularly to the drawings there is indicated at 10 a substantially parabolic metal reflector of the 80 type at present commonly used in automobile lamps. By "substantially parabolic" is meant a reflector as nearly in the shape of a parabola as is possible under present manufacturing conditions. The reflector 10 85 has its interior surface highly polished and is incased and protected by a metal casing 11 which latter is equipped with a removable door 12. The door 12 consists merely of a rim which supports a circular 90 transparent shield 13 preferably of glass.

At the rear of the reflector there is an aperture 14 within which is fixed a sleeve 15 which carries in turn a lamp socket 16, the socket being adjustable longitudinally or 95 axially by means of the screw rod adjustment mechanism shown at 17. The socket 16 offers a means for receiving an electric lamp 18 in the shape of a bayonet joint 19. The lamp is of usual construction having a 100 filament 20 which it is intended should occupy a position as nearly as possible centrally with respect to the focal point of the parabolic reflector. In the embodiment of the invention shown in Fig. 1, perforations 105 21 and 22 in the upper portion of the reflector serve to let the light from the lamp filament penetrate the body of the reflector. A screen 23 is arranged upon a bracket 24 the latter being fixed to the outer surface of 110

the reflector as shown in Fig. 1. This flat bottom portion which is perforated as indicated at 31. The screen 32 is mounted in a frame 33 at the front of the housing and indications corresponding to those shown in Fig. 3 at 25 are made upon the screen. In this form of the invention the light from the filament 20 penetrates the housing 30 through the aperture 31 and is reflected forwardly in the ordinary way by the reflector. If the filament is forwardly or rearwardly of the focal point the reflected beam 34 will be inclined downwardly or upwardly and will not be centrally distributed about the indicating cross. When the filament is in its correct position the reflected beam will project along a line parallel with the axis of the reflector and will be centrally disposed of the indicating cross.

15 By manipulating the adjusting device 17, the lamp bulb and its filament may be moved axially and this movement is given by the operator until such time as the spot on the screen 23 is centrally distributed about the indications or characters on the screen. In Fig. 3 of the drawings these indications are shown at 25, in the form of crosses. It will be noted that there are three perforations and three indications. One of 25 these, for instance the central one, may serve to determine the correct position of the filament along the focal axis. The other two will serve to demonstrate whether the filament is sufficiently within the focal axis 30 or whether it is displaced transversely thereof. Similar means are shown in the drawing for adjusting the filament in a plane transversely of the focal axis and it is within the scope of the invention to provide such means. There is some flexibility in the bayonet joint and socket arrangement at the rear of the reflector which permits some displacement and equally as well permits a slight movement of the lamp laterally to bring the filament into proper position in a transverse plane. Such adjustment may be had by rotating either or both rods 26 and 27, which are 90° apart about the reflector and cross levers 28 and 29, 40 which give a lateral movement of the socket in the casing fastened to the rear of the reflector. A combination of both adjustments effects a resultant adjustment in any desired lateral direction. It is also true that there is little uniformity in the position of filament with respect to the pins of the lamp bulbs which serve to make the bayonet joint. For this reason if a lamp is burned out and another one substituted the filament 50 may be a considerable fraction of an inch one way or the other from the position of the filament in the lamp formerly in place. This lack of uniformity is true in a transverse direction as well as in a longitudinal 55 direction and it is as a practical matter necessary to refocus the device each time a lamp bulb is replaced.

In the modification shown in Fig. 4 a housing 30 is provided on the inner surface of the reflector. This housing has a

Figs. 5 and 6 show another modification 85 wherein the beam is allowed to penetrate an aperture 40 formed in the bottom wall 41 of a housing 42 which housing is provided with a sight 43 through which an operator may view a screen 44 arranged upon the inner surface of the reflector within the housing. This screen is provided with an indicating cross 45 as shown in Fig. 6.

While in the embodiments of the invention shown and described herein a "substantially parabolic" reflector is included, the invention is of course adapted to be used with other forms of reflectors. Any reflector adapted to direct light rays in a given direction and having a main focal point or region would be capable of advantageous use with the focus determining means of my invention. There are numerous reflectors in present day usage based generally on parabolic principles but modified to confine the beam to a low level or to spread the beam fan shape and in combination with these the invention finds particularly advantageous application.

110 Inasmuch as it is usual in the construction of lamps for automobile head-lights to highly polish the reflecting surface it is desirable that the reflector should be completely inclosed within the body of the lamp. In order to facilitate the reading of the optical devices, and obviate the necessity of removing the reflector from the casing a transparent element 50 is arranged in the casing opposite the screen of the optical device.

115 While I have herein described and shown upon the accompanying drawing a few embodiments of the invention, it is to be understood, however, that the invention is not limited to the particular forms, details and arrangement of parts described and shown, but that other forms, details and arrangement of parts are comprehended by the invention, as do not depart from the spirit 120 125 130

of the invention and the scope of the appended claims.

What is claimed as the invention is:—

1. In a device of the character set forth, 5 in combination, a reflector adapted to receive light rays from a focal region and to reflect said rays into a beam of light, an electric filament, means for adjustably supporting the filament in said reflector to bring it into proper position relatively to 10 said reflector, and means comprising a perforation in said reflector, and a screen fixed on said reflector opposite said perforation and adapted to coöperate with light rays 15 passing from said filament through said perforation to said screen to enable an operator to determine the position of said filament relatively to said reflector.
2. In a lamp, in combination, a reflector 20 having a focal axis and a focal point lying

within said axis, a filament adjustably supported in said reflector and adapted to be positioned along said focal axis, a screen on said reflector having an indicator, said reflector being perforated to permit light 25 rays from said source to be transmitted to said screen in definite relation to said indicator.

3. In a lamp, in combination, a casing, 30 a reflector therein, and shaped to project light in concentrated form, an electric filament adjustably mounted in said reflector, an optical device forming an integral part of said reflector and adapted to indicate the relative positions of said filament and 35 reflector, and a transparent member in said casing opposite said optical device for permitting observation of said optical device.

E. F. WACKWITZ.
